WRENCH

Louis E. Hewitt and Truman V. Ellis,
Belding, Mich.

Application October 16, 1940, Serial No. 361,455

1 Claim. (Cl. 81—111)

The present invention relates to new and useful improvements in wrenches.

An object of the invention is to provide a wrench which will be simple in operation.

Another object of the invention is to provide a wrench which will operate equally as well on square nuts as on hexagon nuts.

Another object of the invention is to provide a wrench which may be operated in a ratchet wrench-like manner.

Other objects of the invention are to provide a wrench which will be comparatively light in weight, strong and durable, reliable in use and which may be manufactured at low cost.

Still further objects and advantages of the invention will become apparent from a study of the following specification, taken in connection with the accompanying drawing, wherein like characters of reference designate corresponding parts throughout the several views, wherein:

Figure 1 is a top plan view of a device embodying the invention.

Figure 2 is a side elevational view of the invention.

Figure 3 is a fragmentary elevational view with parts broken away and shown in cross section.

Figure 4 is an end elevational view of the invention.

Referring now to the drawing in detail, it will be seen that the reference numeral 5 designates a handle, constructed of any suitable metallic material, one end portion of which is fashioned to form a head 6 which is of greater thickness than the handle 5.

The head 6 is notched to provide a rigid jaw 7 the working face of which is opposite an arm 8 which is of reduced thickness. Arcuate shoulders 9 and 10 are formed at the base of the arm 8. The outer end portion of the arm 8 is curved, as shown at 11 in Figure 3 of the drawing and has an opening 13 extending transversely therethrough. The face 13 of the head 6 intermediate the jaw 7 and arm 8 is at a right angle to the face of the jaw 7 for a distance and is then directed at an angle to provide a notch 14 one side of which is formed by a pivoted jaw 15.

The pivoted jaw 15 is constructed to conform with shape of the jaw 7 in order that a nut may be positioned between the jaws 15 and 7 and be turned by the same. Jaw 15 on its side opposite its working face is gouged out to provide cheek plates 16 and 17 which have tapered openings 18 and 19 therein. The cheek plates 16 and 17 are joined along one side edge and at one end of the pivoted jaw 15 by the web portion 20 which

provides the working face of the pivoted jaw 15. This web portion 20 on its surface opposite the working face 20 conforms with the configuration of the inside of the arm 8 and curves around the end thereof to provide an abutment 21 which limits the outward swing of the pivoted jaw 15 by contacting the outer surface of the arm 8, as shown in Figure 3 of the drawing.

A pin 22 extends through the openings 12, 18 and 19 and serves as a pintal for the jaw 15. The end portions of the pin 22 are swaged in the tapered openings 18 and 19 and the ends of the pin are flush with the outside surfaces of the cheek plates 16 and 17 to provide a smooth 15 finish.

When the wrench is used to turn a nut the jaws 7 and 15 are placed about the square nut 23 as shown in Figure 1. After placing the jaws in this position the handle 5 is swung in a clockwise direction to turn the nut 23. If a new grip on the nut is desired the handle 5 is swung in a counterclockwise direction at which time the arm 8 swings on the pin 22 and causes the jaw 7 to swing clear of the nut, as shown in Figure 3 of the drawing. With the jaw 7 disengaged from the nut the jaw 15 is then slid around the nut, by manipulating the handle 6, to engage a new face on the nut 23 or 24. Then the handle 6 is again swung in a clockwise direction to further turn the nut. The wrench may be reversed to turn a left hand threaded nut.

Although I have shown and described herein a preferred embodiment of my invention, it is to be definitely understood that I do not desire to limit the application of the invention thereto, and any changes may be made in the structure and arrangement of the parts, within the spirit of the invention as claimed.

What is claimed is:

A wrench including a handle, a fixed jaw at one end of said handle, said jaw having an inner gripping face and an outer gripping face each face being in a plane substantially at right angles to the other, a second inner gripping face on said fixed jaw being in a plane substantially at an angle to said first-named inner gripping face and said outer gripping face, a reduced portion on said handle to provide a fixed arm opposed to said fixed jaw, said fixed arm having an opening therethrough and further having its outer end surface in an arc substantially concentric with the opening, one side edge of said arm terminating in spaced relation to said second inner gripping jaw, a swingable jaw having an opening therethrough, a pin extending through said

openings to pivotally secure the movable jaw on said arm, said swingable jaw being gouged to provide cheek plates on opposite sides of said fixed arm, a web between said cheek plates, one side surface of said web providing an outer gripping face and an inner gripping face on said swingable jaw each being in a plane substantially at right angles to the other, and a second inner

gripping face on said web in a plane substantially at an angle to both the outer and first-named inner faces on said swingable jaw and intersecting said first-named second inner face on said fixed jaw to provide a notch midway between said fixed and swingable jaws.

LOUIS E. HEWITT.
